CLAIM

We claim, the ornamental design for an air conditioner condensing unit, as shown and described.

DESCRIPTION

FIG. 1 illustrates a first perspective view of the air conditioner condensing unit;

FIG. 2 illustrates a second perspective view of the air conditioner condensing unit;

FIG. 3 illustrates a front view of the air conditioner condensing unit;

FIG. 4 illustrates a rear view of the air conditioner condensing unit;

FIG. 5 illustrates a right side view of the air conditioner condensing unit;

FIG. 6 illustrates a left side view of the air conditioner condensing unit;

FIG. 7 illustrates a top view of the air conditioner condensing unit; and,

FIG. 8 illustrates a bottom view of the air conditioner condensing unit.

The broken lines in the drawings illustrate portions of the air conditioner condensing unit that form no part of the claimed design.
